UNITED STATES PATENT OFFICE.

GEORGE CHICKEN, OF LODI, NEW JERSEY.

TOOTHBRUSH.

1,409,830.

Specification of Letters Patent. Patented Mar. 14, 1922.

Application filed January 4, 1921. Serial No. 434,931.

To all whom it may concern:

Be it known that I, GEORGE CHICKEN, a citizen of the United States, residing at Lodi, in the county of Bergen and State of New Jersey, have invented certain new and useful Improvements in a Toothbrush; and I do hereby declare the following to be a full, clear, and exact description of the invention, such as will enable others skilled in the art to which it appertains to make and use the same.

The object of the invention is to provide a tooth brush adapted for more effective operation upon the teeth and more especially of a construction which will facilitate the simultaneous brushing of both the anterior and posterior surfaces of the teeth as a means of removing accumulations and maintaining a sanitary condition; and with this object in view the invention consists in a construction and arrangement of parts of which a preferred embodiment is shown in the accompanying drawing, wherein:

Figure 1 is a side view of a brush embodying the invention.

Figure 2 is a top plan view of the brush, and

Figure 3 is a section taken on the plane indicated by the line 3—3 of Figure 2.

The brush head 10 with which is connected a handle 11 of the usual or any preferred form is bifurcated or forked at its forward end to provide supplementary brush head or tongues 12 and 13 of slightly curved or arculate form the body portions of the tongues being substantially parallel and the inner tongue forming a curved extension of the body portion of the head and being provided in common therewith with bristles 14. Also the facing surfaces of the tongues carry bristles 15 and 16 of which the terminals are almost, if not quite, in contact, the bristles being arranged in the planes of the tongues and projecting toward each other so that in the use thereof, the fork or bifurcation may be arranged to straddle the teeth to bring the bristles carried respectively thereby into contact with opposite surfaces of the teeth. In practice the bristles 16 may be formed as continuations of the bristles 14 which project in the opposite direction from the said tongue and combine with

the bristles on the body portion of the brush head to form a continuous rubbing surface which may be used in the ordinary way. 55

It will be seen that in practice that the brush provided with the feature indicated may be used endwise, that is with the handle depressed in operating upon the upper teeth, the brush being reciprocated longitudinally, 60 and may be correspondingly used upon the lower teeth by reversing the position or extending the handle upward, so as to reach every crevice between the teeth for the removal of any foreign substances which may 65 have become lodged therein.

The under surface of the brush head including the body portion thereof and the extension provided by the under surfaces of the tongues 12 and 13 is preferably of ar- 70 cuate form with the bristles 14 slightly reduced in length toward the extremity of the tongue. The bristles carried by the facing sides or surfaces of the complementary tongues constituting the fork or bifurcation 75 are necessarily short.

Having thus described the invention, what I claim is:—

1. A toothbrush comprising a handle diverging brush heads at one end thereof, and 80 bristles extending from the adjacent faces of the brush heads and from the lower face of each of said brush heads.

2. In a toothbrush comprising a handle and a brush head, bristles each passing 85 through the brush head and having the ends thereof projecting beyond surfaces of the brush head which are at an angle to each other, whereby the ends of each bristle will be disposed at an angle to each other. 90

3. A toothbrush comprising a handle, diverging brush heads at one end thereof, and bristles each passing through one of the brush heads and having the ends thereof projecting beyond the adjacent surfaces and 95 from the lower faces of said brush head, whereby the ends of each bristle will be disposed at an angle to each other.

In testimony whereof I affix my signature in presence of two witnesses.

GEORGE CHICKEN.

Witnesses:

CORINNE STARNATO,
ANNA CIAMPO.
